COMBINED FERTILIZER TANK AND MOUNTING

William N. Glover, Jr., Wilson, N.C., assignor to General Metals, Inc., Greensboro, N.C., a corporation of North Carolina

Filed June 12, 1967, Ser. No. 7,451

Term of patent 14 years

(Cl. D23—3)

FIG. 1

FIG. 4

FIG. 2

FIG. 5

FIG. 3

FIG. 1 is a front perspective view of a combined fertilizer tank and mounting embodying my invention with the pump cover in open position.

FIG. 2 is a reduced top plan view of FIG. 1 with the pump cover in a closed position;

FIG. 3 is a side view of FIG. 2;

FIG. 4 is a right end view of FIG. 3; and

FIG. 5 is a left end view of FIG. 3.

I claim:

The ornamental design for a combined fertilizer tank and mounting, as shown and described.
